ROTARY MANIFOLD

BACKGROUND OF THE INVENTION

One type of spray machine coats materials moving beneath it from spray guns which are attached on long arms similar to spokes of a wheel. As the arms turn the coating is sprayed over the material as the guns pass above it and the guns are then turned off as they continue out beyond the edge of the material. Manifolds are used to distribute an atomizing air stream, an air stream to turn the spray guns on and off and a coating fluid from central reservoirs to each gun on the arm. The fluids enter one central outlet of a distribution chamber for each fluid and are equally distributed to each spray gun along the arm by some suitable means such as a hose.

A manifold for spray apparatus of this type which utilizes one set of inlet conduits, one conduit inside the other, for feeding atomizing air and coating liquid into a series of distribution chambers in the manifold, is well known in the coating art. However, these manifolds have certain disadvantages:

1. The atomizing air, being under higher pressure than the coating fluid, has a tendency to leak, entraining many small air bubbles into the liquid fluid line. These bubbles can cause defects in the finished goods.
2. The manifolds now in use allow for the convenient application of only one coating fluid stream.

SUMMARY OF THE INVENTION

Expressed broadly, the invention provides a manifold useful for the concurrent spray coating of at least two different coating fluids. In the manifold there is complete separation of the air lines from the coating fluid lines by the use of two sets of conduits. Each set of conduits contains several passageways leading into the cylindrical housing or mandrel member, containing the distribution chambers. The two sets of conduits enter said mandrel member from opposite ends and lie in a straight line along a central axis of rotation through the bases of the mandrel.

By separating the air and coating fluid lines into two sets of conduits, the air cannot bleed into the coating fluid. Any leaking between the several air conduits will be inconsequential and bleeding in the coating fluid conduits is less likely since all fluids will be at equal, relatively low pressures. The separation into two conduit sets also facilitates the convenient simultaneous application of more than one coating fluid. This capability makes possible new aesthetic effects on substrate materials by permitting two or more coating fluids to run together during application producing a swirled or marble cake effect.

BRIEF DESCRIPTION OF THE DRAWINGS

References may be made to the attached drawing in which: FIG. 1 is a perspective view of the apparatus of the invention.

FIG. 2 is a perspective view of one nonrotatable means of securing the device and introducing the fluids into the conduits.

FIG. 3 is a vertical central section view of the apparatus of the invention and the nonrotatable support means shown in FIG. 2.

FIG. 4 is a side view schematic illustration showing the position of the apparatus of the invention relative to the spray guns of one type of spray apparatus.

FIG. 5 is a top view schematic illustration showing the position of the apparatus of the invention relative to the same spray apparatus as in FIG. 4 and also showing the position and relative size of the substrate materials to be coated.

DESCRIPTION OF THE PREFERRED EMBODIMENT

A central vertical section view of the preferred embodiment is shown in FIG. 3. The entire manifold is symmetrical around the line A through the mandrel member 13. The air or coating fluid enters one of the conduit sets 4, and passes along the

passageways 5 and 6. Passageway 5 forms the center of the conduit set with the second passageway 6 formed around it, as would be the case for all succeeding passageways. The set of conduits comprising 5 and 6 proceed into the distribution chambers contained in mandrel 13. As the set passes through the solid wall 10 of the distribution chamber 7 the outside passageway 6 empties into 7. The other conduit passes through chamber 7 to its distribution chamber 12. The fluids are distributed from the chambers by outlets 8. The mandrel 13 and conduit sets 4 may be secured and the fluids may be introduced into the passageway by any suitable means.

One means of securing the device and feeding the passageways is shown in FIG. 2 and also in the FIG. 3 section drawing. The fluid enters chambers 3 and 11 through inlet 2 where they pass into passageways 5 and 6 respectively. The block 1 is secured to the spray apparatus frame such that the device is oriented in the manner shown in FIGS. 4 and 5, for one type of spray apparatus. A rotary seal prevents the fluid leaking at the point 9 where the conduit set joins the block 1.

FIG. 5 shows material to be coated moving in the direction of the arrows in the top corners. The spray guns mounted on arms 15 and 16 rotate in the direction indicated by the arrows around the axis of rotation 18. These guns are turned on at point 13 by an air line and turned off by said air line at point 14. Two fluid coatings are fed to alternate guns (that is, one to guns 15 and one to guns 16) which apply the coating simultaneously, thus allowing them to run together producing a swirled or marble cake effect.

30

EXAMPLE 1

With reference to FIG. 3, atomization air under a pressure of 85 p.s.i.g.; is fed into chamber 3 through inlet 2 while cylinder air, which operates an on-off mechanism in the spray apparatus is fed into chamber 11 under a pressure of 50 p.s.i.g. The atomization air flows into distribution chamber 12 where it is distributed to the eight spray guns of a spray apparatus as in FIG. 5. Black and white coating fluids having a viscosity 20 cps., are fed into the other conduit set in the same manner under equal pressures of 5 to 10 p.s.i. The black coating flows at a rate of 0.1 gal./min. from chamber 19 to distribution chamber 20 which is adjacent to chamber 12. The juncture of the walls of chambers 12 and 20 forms a line of symmetry A, 35 midway between the bases of the mandrel. The white coating flows at a rate of 0.2 gal./min. from chamber 22 to distribution chamber 21. The two coatings are then distributed to alternate spray guns, black to guns 15 and white to guns 16. The dimensions of the mandrel are 4 inches base diameter and a height of 40 8 1/2 inches. Each set of conduits is 15 inches long and the passageways are circular tubes of 5/8 inches and 1 1/8 inches outside diameter respectively. The length of the spray gun arms shown in FIG. 5 is 9 feet and the width of the material is 55 7 feet moving at a rate of 30 f.p.m. The angular velocity of the spray apparatus is 2.6 rad./sec., thus each gun is turned on and off at 0.6 sec. intervals. The spray guns define one plane in which they all lie and the manifold is oriented as in FIG. 4 with respect to said plane.

50

I claim:

1. A rotary spray apparatus consisting essentially of:
  - A cylindrical manifold comprised of:
    - four distribution chambers;
    - each of said chambers being separated from each of the other chambers by a solid wall;
    - each chamber containing eight outlets; and
    - each chamber being supplied by one concentric conduit feed line;
  - two concentric conduit fluid feed lines, one inside the other, which enter one end of the cylindrical manifold, said two concentric conduit feed lines being comprised of:
    - an inside conduit which enters a separate distribution chamber within the manifold supplying coating fluid of a particular type and color to that chamber for

65

75

- further distribution to one half of the total number of spray guns; and
- b. an outside conduit which enters another separate distribution chamber for supplying a different type and color of coating fluid to the chamber for further distribution to the remaining one half of the spray guns; and
3. two concentric conduit air lines, one inside the other, which enter the opposite end of the cylindrical manifold, said two concentric conduit air lines being comprised of:
- a. an inside conduit which enters a separate distribution chamber for supplying atomized air to the chamber for further distribution to all the spray guns; and
- b. an outside conduit which enters a separate distribution chamber for supplying air from an intermittent spraying control device to the chamber for further distribution to all the spray guns.

B. An air operated intermittent spraying device connected to a distribution chamber on the air side of the four-chambered cylindrical manifold by concentric air feed lines, which is adapted to turn the spray guns on when the guns are over the material being sprayed and off when the guns are not over the material; the on/off cycle being controlled at an average of 0.6 second intervals with the spraying apparatus rotating at a velocity of 2.6 radii per second and operational air being supplied by cylinder air at 40 to 60 p.s.i.

2. A manifold as in claim 6 having two blocks secured to the spray apparatus, each block being used for supporting the manifold and for introduction of fluid into the concentric conduit feed lines of the manifold, each of said blocks containing an inlet chamber for each passageway of the conduit which in turn leads to the individual manifold distribution chambers.
